UNITED STATES PATENT OFFICE

LINUS E. RUSSELL, OF SPRINGFIELD, OHIO, ASSIGNOR OF ONE-HALF TO GEORGE E. PETERS, OF SPRINGFIELD, OHIO

AUTOMOBILE CONTROL

Application filed August 29, 1928. Serial No. 302,842.

My invention relates to control devices for motor vehicle engines, and more particularly to a single manually operable control element common to both the starter switch and the carburetor choke or priming device. In a new type of popular motor vehicle recently introduced, the starter pedal is located in an extreme forward position upon the foot board, and the choke or priming control is distantly located toward the right side of the dash, where such devices are inconvenient for approximately simultaneous operation.

In the present invention, a single operating rod extending within easy and convenient reach of the driver, is operatively connected directly with the starter switch plunger and connected through a flexible Bowden wire connection with the carburetor, whereby a rocking motion of the control rod will effect progressive adjustment of the carburetor choke or priming mechanism, a thrust or bodily endwise movement of the rod will operate the starter switch.

The present construction is a further development and embodiment in a simple and inexpensive form of the control device illustrated in co-pending application, L. E. Russell and G. E. Peters, No. 261,953, and No. 283,988.

The object of the present invention is to simplify the construction as well as the mode and means of operation of such vehicle motor control devices, whereby they will not only be cheapened in construction, but will be more efficient in use, effective in operation, uniform in action, conveniently accessible, easily operated, and unlikely to get out of repair.

A further object of the present invention is to provide a control device of extremely simple form and of few parts, which may be economically manufactured, to be sold at a popular price, which may be quickly and easily applied to the popular type of motor vehicle before mentioned.

A further object of the invention is to enable the location of the motor starter and fuel regulating means within easy reach of the driver in order that these devices may be conveniently and easily manipulated while main-

taining normal driving position and perfect control of the steering wheel.

A further object of the invention is to provide a common control device for two or more operative mechanisms which may be readily and quickly applied to existing vehicles without reconstruction or rearrangement of parts by persons unskilled in mechanical trades.

A further object of the invention is to provide such control means, utilizing so far as possible, the existing parts of the standard motor vehicle.

With the above primary and other incidental objects in view, as will more fully appear in the specification, the invention consists of the features of construction, the parts and combinations thereof, and the mode of operation or their equivalent as hereinafter described and set forth in the claims.

Referring to the accompanying drawings wherein is shown the preferred but obviously not necessarily the only form of embodiment of the invention, Fig. 1 is a perspective view beneath the hood of a motor vehicle, showing the motor starter and the control device operatively connected thereto. Fig. 2 is a perspective view of a portion of the dash of a vehicle showing the relative position and mounting of the control member. Fig. 3 is a detail plan view. Fig. 4 is a side elevation of a portion of the vehicle motor showing the operative connection with the carburetor choke arm.

Like parts are represented by similar characters of reference throughout the several views.

Referring to the drawings, 1 indicates the floor board of the vehicle body as viewed from beneath. Extending through the floor board is the usual steering post 2, beside which is located the starter 3 for the vehicle motor 4. Mounted on top of the starter 3 is the starter switch housing 5, controlled by a depressible plunger 6 loosely mounted for both reciprocatory and rotary motion within an upwardly and rearwardly inclined guide sleeve or socket 7. The upper end of this switch plunger 6 is counterbored to receive the stem of the usual starter pedal which projects through the floor board 1 and is engaged with

such switch plunger 6 by a cotter pin 8 in the original construction as supplied by the manufacturer. At the opposite side of the motor 4, from that shown in Fig. 1, there is located a carburetor 9 provided with an oscillatory arm 10 which controls a carburetor choke or priming valve.

The construction thus far described is that found in a popular type of motor vehicle before mentioned and forms no part per se of the present invention.

In applying the present control device to such motor vehicle, the original starter pedal is removed by withdrawal of the cotter pin 8 and disengagement of the pedal stem from the plunger 6. There is then substituted for such pedal stem an elongated operating rod 12 of sufficient length to extend beyond the dash or cowl board of the vehicle, and into convenient reach of the driver. The lower end of this control rod 12 is inserted within the counterbore or socket in the end of the switch plunger 6, and is secured thereto by the return of the cotter pin 8 through registering holes in the switch plunger and the end of the control rod in the same manner that it formerly connected the stem of the starter pedal.

To support the upper end of the control rod 12, there is provided a bracket arm 13 secured to the lower side of the instrument housing 14 upon the cowl board or dash 15. As supplied by the manufacturer, this instrument housing 14 is attached by two screws 16 which, in the present instance, are utilized for attachment of the bracket arm 13. The bracket arm 13 is provided at its extremity with an eye or loop 17 preferably, though not necessarily, enclosing a bushing sleeve through which the control rod 12 extends. This control rod 12 carries at its upper end a knob or button 19 by which the rod may be longitudinally depressed through the guide afforded by the mounting arm 13 in order to depress the switch plunger 6. The rod is also capable of to and fro rocking motion, the degree of rocking adjustment being determined by a mark or pointer 21 upon the button or knob 20.

Fixedly secured to the control rod 12 below the foot board 1 is a rock arm 22 which carries at its extremity a pivotally mounted stud or swivel 3 with which is connected one end of a flexible operating wire 24. The wire 24 comprises the reciprocating element of a Bowden wire connection, the casing or guide tube 25 of which is secured in an eye or sleeve 26 formed by the curled end of a bracket 27. This bracket 27 is secured in position by a bolt 28 projecting through the floor board of the vehicle and which is a part of the original vehicle construction. At its opposite end, the guide tube 25 is secured to a bracket 29 attached to the carburetor 9, while the extremity of the reciprocating wire 24 is operatively

engaged with the choke arm 10 of the carburetor.

In operation the rod 12 is rocked to and fro to oscillate the actuator arm 22 and thereby reciprocate the flexible wire connection 24 to adjust the priming or choke arm of the carburetor 9. Such rocking motion of the control element is effected wholly independent of its thrust or reciprocatory movement and independent of the operation of the starter switch. During such rocking adjustment effective to adjust the carburetor the switch plunger 6 is given a corresponding rocking or rotary motion in unison with that of the rod 12. When it is desired to start the motor, the rod 12 is depressed longitudinally thereby depressing the starter switch plunger 6 wholly independent of the rocking adjustment of the arm 22 and the reciprocatory adjustment of the wire 24. The depression of the plunger 6 closes the starter circuit in the usual manner, just as though the original starter pedal was connected therewith. During such reciprocatory motion of the control rod 12, the arm 22 moves with it, there being sufficient flexibility in the actuator wire 24 to permit such adjustment without interfering with the operative action of such wire. That is to say, the arm 22 responds to both the rocking and thrust motion, the rocking motion being effective to adjust the carburetor choke or arm independently of the starter and the thrust motion being operative to close the starter switch regardless of the operative position of the rock arm. Cross reference is made to my co-pending applications pertaining to analogous subject matter, to wit, Ser. No. 261,953, filed Mar. 15, 1928; Ser. No. 283,988, filed June 8, 1928; Ser. No. 306,543, filed Sept. 12, 1928; Ser. No. 308,289, filed Sept. 25, 1928; and Ser. No. 317,467, filed Nov. 5, 1928.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific details shown, but that the means and construction herein disclosed comprise the preferred form of several modes of putting the invention into effect and the invention is, therefore, claimed in any of its forms or modifications within the legitimate and valid scope of the appended claims.

Having thus described my invention, I claim:

1. Manually operable means for adjusting the carburetor and operating the starter

switch of a vehicle motor, comprising an oscillatory arm capable of bodily movement independent of its oscillatory motion in a direction angular to its direction of oscillation, an operative connection between the arm and carburetor, controlled by the oscillatory motion of the arm, and an operative connection between the arm and the starter switch whereby the switch is closed upon the bodily movement 10 of the arm.

2. The combination with a motor starter switch having a depressible plunger, of a rod connected directly with said plunger and extending into proximity with the dash of 15 a motor vehicle, a rock arm carried by the rod, and a reciprocatory connection between said rock arm and the adjusting element of a motor carburetor, whereby a thrust motion of said rod will operate the starter switch independent of the adjustment of the carburetor, and a rocking motion of the rod will actuate the carburetor adjusting element 20 independent of the operation of the starter switch.

3. The combination with a motor vehicle 25 starter switch having a longitudinally depressible plunger, the end of which is counter-bored to receive an actuator stem and a transverse coupling pin for connecting the stem, said plunger being revolubly mounted, of an 30 elongated reciprocatory rod projecting within the counterbore of said stem and connected thereto by the transverse coupling pin, said rod extending through the foot board of a motor vehicle and into proximate relation to the 35 dash of the vehicle, said rod being capable of both rocking and endwise adjustment, and a flexible reciprocatory actuator wire operatively connecting the control rod with the adjusting element of the motor carburetor 40 whereby the starter switch is operated by an endwise thrust of said rod independent of the carburetor adjustment, and the carburetor is adjusted by a rocking motion of the rod independent of its endwise thrust motion.

4. In an apparatus of the character described, a control rod having one end operatively connected with the starter switch of a motor vehicle, said rod extending through the floor board of the vehicle into convenient 50 grasping distance of the driver, a rock arm fixedly secured to the rod, a flexible reciprocatory connection between the rock arm and an adjusting element of the motor carburetor, said rod being capable of independent endwise 55 thrust and rocking motions whereby the starter switch and carburetor adjusting member may be independently actuated by said motions of the rod.

5. The combination with a depressible 60 plunger and a distantly located member to be independently actuated, of a control member capable of independent rocking and longitudinal motion, a Bowden wire transmission element connecting the distantly located member with the control member for actuation

by rocking adjustment of the latter, said control member being operatively connected with the depressible plunger for transmitting motion thereto by the longitudinal movement of the control member independent of its rocking motion. 70

In testimony whereof, I have hereunto set my hand this 25th day of August A. D. 1928.

LINUS E. RUSSELL.
